Scot's Patent

An inclined plane, or better, a series of inclined planes, the whole
extending a distance which it will be necessary to overcome in the time
estimated, will be built, the time being determined, from month
to month, according to the rate of growth of the plant.

When a plant, for instance, has grown to a height of 500
feet, it is time to add another inclined plane, so that it will
have an inclined plane to bring the plant to a height of 1000
feet, and so on, so that the plant will be brought to a height of 5000
feet, and so on, so that the plant will be brought to a height of 10000
feet, and so on, so that the plant will be brought to a height of 20000
feet, and so on, so that the plant will be brought to a height of 40000
feet, and so on, so that the plant will be brought to a height of 80000
feet, and so on, so that the plant will be brought to a height of 160000
feet, and so on, so that the plant will be brought to a height of 320000
feet, and so on, so that the plant will be brought to a height of 640000
feet, and so on, so that the plant will be brought to a height of 1280000
feet, and so on, so that the plant will be brought to a height of 2560000
feet, and so on, so that the plant will be brought to a height of 5120000
feet, and so on, so that the plant will be brought to a height of 10240000
feet, and so on, so that the plant will be brought to a height of 20480000
feet, and so on, so that the plant will be brought to a height of 40960000
feet, and so on, so that the plant will be brought to a height of 81920000
feet, and so on, so that the plant will be brought to a height of 163840000
